UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

INTERMITTENT DRIVING MECHANISM FOR MOTION-PICTURE MACHINES.

1,129,121.

Specification of Letters Patent. Patented Feb. 23, 1915.

Application filed October 4, 1910. Serial No. 585,202.

To all whom it may concern:

Be it known that I, NICHOLAS POWER, a citizen of the United States, residing at Brooklyn, in the county of Kings and State 5 of New York, with post-office address at No. 388 Jefferson avenue, have invented certain new and useful Improvements in Intermittent Driving Mechanism for Motion-Picture Machines, of which the following is a specification.

This invention relates to projecting apparatus, and more particularly to apparatus for projecting moving pictures.

The primary object of the invention is to 15 improve the mechanism, by means of which an intermittent movement is imparted to the strip, or film, bearing the pictures to be projected.

A further object of the invention is to 20 improve the projecting apparatus for moving pictures with respect to the reduction of the wear upon the film in its passage through the apparatus.

Other objects of the invention will occur 25 in the course of the following description in which reference is made to the accompanying drawing in which is illustrated a single embodiment of the invention and in which the corresponding parts are designated by 30 similar characters of reference in the several views.

Figure 1 is a horizontal section through 35 the intermittent movement showing the relation of the driving shaft and driven shaft carrying the feed sprocket; Fig. 2 is an end view from the left of Fig. 1 with the outer portion of the casing removed; and Fig. 3 is a detail view showing the parts in different positions from that shown in Fig. 2.

I have shown my improved intermittent 40 driving gear as applied to a feed sprocket 6 for feeding the film in a moving picture machine past the projecting lens in front of which the successive pictures are momentarily brought to rest for projection on the screen.

The mechanism consists of two members 45 18 and 19, the former comprising a cam 18^a of approximately diamond shape, and the latter consisting preferably of a cross, having four arms 20, arranged at right angles to each other, and each bearing near its outer end a pin 21. The cam member 18 is mounted upon a heavy shaft 22, to which motion 50 is imparted by any suitable means, as for

instance, a suitable gear as indicated in Fig. 1. The driven member 19 is mounted on a spindle 11 which also has bearings in the carriage and is arranged just below the main or cam shaft. The cam member 18 is 6 preferably cut from a single block of steel and comprises in addition to the cam proper 18^a a locking ring 26, which is concentric with the shaft on which the member 17 is mounted. This locking ring is of such width 65 that it will just pass between the pin or studs on the driven member 19, two studs lying within the ring and two without. The ring is incomplete and the ends are spaced from the sides of the cam proper, as shown 70 in Fig. 6. The ends of the ring are so shaped that passages 27, of a suitable width to just permit the studs on the driven member to pass therethrough are left between the ends of the ring and the sides of the cam 75 proper 18^a. When the apparatus is in operation the cam member is driven at a speed ranging from about 800 revolutions per minute to a speed of 1200 or more revolutions per minute, and, as considerable energy 80 is required to impart the intermittent rotation to the driven member 19, its spindle and the sprocket mounted thereon, the member 18, and the spindle upon which it is carried are made quite massive so as to insure rigidity and resistance to wear. It is also preferable that the cam member be made of tool 85 steel and adapted to be tempered, and that the cam proper at least be tempered so as to withstand wear and shock. 90

The spindle 11 is journaled in slightly eccentric bushings 28, 29, the former being small in diameter and the latter relatively large. It will be noted on comparison of the diameters of the bushing 29 and the sprocket 95 carried on the spindle 11, that the bushing is of the larger diameter. The purpose of this construction is to permit the removal of the spindle and the sprocket from its position in the framing carriage without detaching the sprocket from the spindle. This is easily accomplished by merely loosening the screw which holds the bushing in place and sliding the bushing, spindle and sprocket through the opening in the framing 100 carriage provided for the bushing.

To insure long service of the mechanism for imparting intermittent movement to the parts, they are inclosed in a dust-proof casing consisting of an inner part, 30, and 110

an outer part, 31. The former is cast integral with the framing carriage and the latter is in the form of a cap which is secured to the inner member of the casing by 5 means of screws 32.

It will be noted that the general outline of the casing is circular, but a smaller cavity or pocket is formed at the lower part thereof to provide clearance for the turning of 10 the driven member on the intermittent movement. The oiling device 33 is secured on the outer member of the casing adjacent to this cavity to permit the easy introduction of oil into the casing. This oiling device is placed 15 near the bottom of the casing so that it will be impossible to introduce a large quantity of oil into the casing, which is objectionable because of its tendency to work its way through the bearings for the spindles which 20 extend into the casing, and so escape on to the film as it passes through the apparatus.

Owing to the peculiar construction of the members 18 and 19 by which intermittent movement is imparted to the sprocket 6 25 movement is imparted to the sprocket during only about $\frac{1}{5}$ of the time of rotation of the driving member 18 and the intermittent spindle 11 is held perfectly still during the remainder of the rotation of the driving 30 member 18, because during this time the locking ring 26 provided on the member 18 engages all of the pins 21 on the arms 20 of the cross-shaped driven member 19, two of which rest against the inner surface of the 35 locking ring and two against the outer surface. The rotative movement is imparted to the member 19 only when the diamond shaped cam 18^a passes between the pins on the arms of the driven member. At each 40 passage of the diamond shaped cam the member 19 is turned through an angle of 90 degrees, the direction of rotation of the driving and driven members being the same. The cam 18^a is not exactly diamond shaped, 45 but is so designed that it will impart an approximately uniform acceleration to the driven member as one of the pins 21 passes along from the forward end of the cam to the outermost angle thereof, after which a 50 substantially uniform rotation is imparted to the driven member as the pin passes from the outermost angle of the cam to its rear extremity. During the period of acceleration one of the pins passes through the rear 55 passageway 27 between the cam and the adjacent end of the locking ring 26 and during the period of rotation another pin passes through the forward passageway 27. These 60 passageways are of just sufficient width to permit the passage of the pins, thus insuring quiet operation of the intermittent movement and preventing lost motion.

My improved intermittent gear is especially adaptable for moving picture machines because of its uniform acceleration

and retardation, also because of the effective locking of the driven part during the moment of rest. A moving picture machine must work at very high speed and any imperfect action results in injury to the fragile 70 and oft times very valuable film. The cam may be shaped to give any desired ratio of movement and rest. The longer the period of rest relative to the period of movement the better will be the projection. Obviously 75 a gear which will permit the greatest speed of movement without damage to the film will allow the shortest period of movement relative to the period of rest. With the construction shown the ratio of rest to movement is 5 to 1, and so far as I am aware I am the first to produce a successful machine in which the ratio of the period of rest to the period of movement is greater than 3 to 1.

Having thus described my invention, what 80 I claim as new and desire to secure by Letters Patent, is:

1. In a power transmitting mechanism, the combination of a driving member, and a driven member, said driven member having a plurality of spaced projections, said driving member comprising a locking part adapted to pass between and simultaneously engage a plurality of the projections of said driven member and hold said driven member against movement and a driving cam adapted to periodically engage said projections and partially rotate said driven member.

2. In a power transmitting mechanism, 100 the combination of a rotatable driving member, and a driven member having a plurality of spaced projections, said driving member comprising a driving part adapted to periodically engage said projections and partially rotate said driven member and a locking cam comprising an annular flange having a recess adjacent said driving cam, and adapted to pass between the projections of the driven member and simultaneously engage with its opposite edges, a plurality of said projections and hold the said driven member against movement, during the intervals between its movements as effected by said driving cam.

3. In a power transmitting mechanism, 110 the combination of a driving member, and a driven member having a plurality of spaced projections on opposite sides of its center of rotation, said driving member comprising a cam adapted to pass between the projections of the driven member within the circumference of said member and operably engage one of said projections to effect a partial rotation of said driven member and a locking cam adapted to engage said driven member and lock the same against movement during the intervals between its intermittent operations.

4. In a power transmitting mechanism, 120

the combination of a continuously rotatable driving member, and a driven member having a plurality of eccentrically disposed axial projections, said driving member having an eccentrically disposed axial projection adapted to successively engage said projections to effect a partial rotation of said driven member and a locking cam for holding said member against movement during the intervals between its intermittent operations.

5. In a power transmitting mechanism, the combination of a driving member, and a driven member having a plurality of eccentrically disposed projections, said driving member comprising a locking ring or flange having a recess or gap at one point in its circumference and a driving cam consisting of an axial projection located in the 10 gap in said flange and adapted to successively engage the projections of said driven member for effecting its partial rotation.

6. In a power transmitting mechanism, the combination of a driving member, and a driven member having a plurality of eccentrically disposed projections, said driving member comprising a locking ring or flange having a recess or gap at one point in its circumference and a driving cam an axial projection located in the gap in said 25 flange and adapted to pass within the circumference of said driven member and successively engage the projections of said driven member to effect its partial rotation, the ring thereafter engaging a plurality of 30 said projections to hold the driven member against movement during the intervals between its intermittent operations.

In testimony whereof, I have signed my name hereto in the presence of witnesses.

NICHOLAS POWER.
